UNITED STATES PATENT OFFICE

JOHN EDWARD GLOEKLER, OF PITTSBURGH, PENNSYLVANIA

REFRIGERATING CABINET

Application filed December 3, 1929. Serial No. 411,266.

My invention is an improvement in refrigerating cabinets for containing and exhibiting its contents, as meats, vegetables, milk, butter, etc.

5 Fig. 1 illustrates the construction of the visible content portion of the refrigerator in cross section;

Fig. 2 is a detail section taken on line II—II of Fig. 1;

10 Fig. 3 is a complete cross section like Fig. 1, showing an alternative construction including a lower storage compartment.

In cabinets of the same general kind or character as that involved herein, it is usual 15 and customary to provide a main enclosing chamber, surrounded by walls partly of glass for visual inspection from the front, with means for access to the chamber from the rear and having communication with an adjacent 20 refrigerating chamber. Such cabinets are usually more or less elongated, of rectangular form mounted upon a lower supporting base or frame adapted to be arranged in a store room singly or in series in the manner of a 25 counter or counters, for convenient inspection from the front and access from the rear, and provided with one or more flat top portions for placement of merchandise or other articles of different kinds.

30 In my present invention I utilize the main essentials of such cabinets, in which there is a general conformity to established construction and design, but I have incorporated in the refrigerator certain special constructions 35 as to the main and supplemental chambers contributing to efficiency of design and operation as well as of structural advantage and novelty, as hereinafter described.

I also show a modified construction in 40 which the said main and supplemental communicating chambers are incorporated, with a supporting and enclosing casing embodying a lower storage chamber having a definite related connection with the upper chambers.

45 Referring to the drawings, illustrating the construction in cross section, Figs. 1 and 2, A is the main food or other article containing chamber located above a bottom main supporting floor 2 upon which is laid a comparatively thick body 3 of comminuted cork or

other suitable insulating material. Such body occupies and constitutes the main lower bottom portion of chamber A extending between longitudinal timbers or braces 4 carried on the base and arranged backwardly 55 from a front panel or wall 5, of wood or other suitable material.

Backwardly from the rear timber 4 the main bottom 2 extends on a common plane and a similar bottom 6 is co-extensive there- 60 with to the rear, with a terminal longitudinal panel or covering board 7. The extreme front and rear portions of such base or flooring are mounted upon and supported by any suitable under frame, as posts or legs 8.

The top portion of chamber A is covered 65 and enclosed by a relatively narrow longitudinal top 9 of glass or other suitable material, rigidly supported upwardly at the proper height by continuous framing, as metal bars 70.

10 Said bars project backwardly and downwardly along the upper rear portion of the chamber at both ends or at intermediate positions, and then downwardly as at 10a, terminating in off-set flanges or shoes 11. The 75 front of the chamber is covered by one or a plurality, preferably two, of plates of glass 12 for visibility of the interior, said plates having an intervening air space 13.

The plates are properly framed together 80 at the bottom as by intervening strip 14, and rest upon the beveled upper edge of the lower front panel 5. The plates 12 extend upwardly at the desired inclination, terminating below the under front portion 85 of top 9. Underneath the top 9 I insert an insulating slab 35, of cork or other suitable material, into which the upper edges of plates 12 are framed by rebated engage- 90 ment, as shown.

At the upper rear portion of the cabinet I arrange longitudinal framing strips 15—16 resting against and supported by the plural bars 10, which strips provide for sliding 95 mounting thereon of one or more opening and closing doors 17 preferably provided with glass window plates or panes 18. By shifting such doors to the right or the left the interior cavity may be opened or closed 100

for placement or removal of goods or commodities, as meats, butter, etc.

Extending laterally back from the lower strip 16, and framed thereinto, is the rear 5 lower covering top 19 of board or other suitable material, supported underneath its rear edge by the upper framing member 20, corresponding to the lower panel 7 and connected therewith by the intervening 10 panel 21.

By means of the construction just described I provide, by the top 19, panel member 20—21—7, and bottom 6, a longitudinal rectangular construction providing for the 15 supplemental communicating refrigerating chamber *a*. Said chamber is provided for the purpose of holding refrigerating material as ice, or a coil of refrigerating pipes or the like, as preferred. It is completely 20 insulated at top, back, and bottom by relatively thick back and bottom wall fillings 22—23 of granulated cork or other suitable insulating material, which portions are continuously stationary and provide incorporated 25 inner wall and bottom members of the rear structure.

Secured to the under side of rear shelf or lower top member 19 is a similar insulating lining body 24 of cork or other suitable 30 material, forming a portion of and removable with the outer shelf member 19. Said composite member is relatively movable as by upward lifting or longitudinal sliding, for opening and closing the interior chamber *a*.

Between the rear insulating bottom 23 and the bottom portion of the main chamber A is a longitudinal strip 25 of wood or other suitable material, resting upon and extending 40 above the member 4 and having an upper rounded edge as shown:

At the front bottom portion of chamber A is a similar strip 26, resting upon member 4 and against the rear upper edge portion 45 of panel 5, such members 25 and 26 forming the rear and front comparatively narrow limiting walls of the main bottom portion of said chamber.

A continuous lining 27 of sheet metal as 50 zinc, copper, or other suitable material, extends downwardly at the rear from the inner top portion of rear wall 22 forwardly across the top of insulation 23, being rounded at the rear corner as at 28 and similarly 55 rounded as at 29, providing a snug supporting base portion for the shoe 11 of standard 10a of the supporting frame bars 10. Lining 27 is continuously bent upwardly around the upper rounded edge of bar 60 25, then downwardly along the front face of said bar, then at right angles across the entire bottom space, resting upon timbers 4 and insulation 3, and is then bent upwardly at the front at right angles to the bottom 65 and over the rounded inner upper edge of

member 26, terminating inside of the inner glass plate 12.

By such construction, utilizing a continuous sheet of metal, the entire permanent face portions of chamber *a* and A are covered and 70 provide a smooth sanitary and serviceable surface, well adapted to the purposes and functions of the construction.

Laid upon the main sheet metal bottom 27 of chamber A is a longitudinal strip or bottom plate 30 of opalite, glass, or other suitable material, constituting the main exposed 75 interior bottom portion of said chamber.

Resting transversely across the width of plate 30, at suitably spaced intervals, are a 80 series of supporting vertical slats or strips 31, in the general arrangement shown in cross section in Fig. 2. The upper edges of strips 31 incline slightly outwardly downwardly toward the front of the casing, so as to conveniently support upon them any suitable articles such as meat, vegetables, etc., or vessels containing the same.

Strips 31 are substantially co-extensive 85 with the interior width space of the bottom cavity between members 25 and 26 and may be loosely mounted therein for removal, or cleaning, or spacing adjustment, as will be readily understood.

It will be observed that the bottom level 90 of sheet metal lining 27 below the chamber A is at a substantially lower position than the corresponding bottom lining 27 of chamber *a*.

Also that the bottom of such latter chamber is confined within the upwardly extending rear and front edge walls whereby to provide a holding basin for any accumulation 100 or moisture.

A further advantage of such arrangement 105 is that the dimensional proportions and arrangement of the chambers is such as to ensure a material elevation of the smaller refrigerating chamber *a* above the lower portion of the larger chamber A, so that the circulation of cold air from chamber *a* to chamber A will be forwardly and downwardly, following the usual course of cold air.

The circulation in such manner is therefore 115 outwardly, downwardly and forwardly toward the front bottom portion of chamber A, between the several supporting strips 31, and underneath the supported articles thereon.

A partition 34 is interposed between chamber A and *a*, spaced at bottom and top as 120 shown, above the upwardly projecting strip 25 and with its upper edge below the inner portion of the cover for refrigerator chamber *a*. By such construction the circulation of air is better directed and controlled, warmer 125 air entering at the top and passing outwardly at the bottom.

The partition 34 is preferably made of 130 glass or other suitable material, and is preferably provided at its front with a mirror

surface for reflection of the contents of the main chamber.

The circulation thereafter is upwardly along the front inner plate 12, around the upper portion of the main chamber and backwardly into the upper portion of the refrigerating chamber for repetition of the same general circulation, as indicated by the circulating arrows.

10 One or more supplemental shelves 32 may be located at convenient positions in the upper front portion of the main containing chamber A as shown, resting upon any suitable brackets at the ends, as will be readily understood.

Arranged adjacent to such shelves, preferably underneath as shown, are circulating cooling pipes 33 adapted to maintain refrigerating action around the shelves and for heat absorption action on their contents.

20 The upwardly ascending currents of warmer air are thus again reduced in temperature at such zones of location. Additional cooling pipes 33 are similarly arranged along underneath the insulating slab 35, at the extreme upper portion of chamber A, for similar action in assisting further cooling of the upper currents of air.

In Fig. 3 I show a further enlarged development of the construction, utilizing a lower storage chamber B. In such construction front and back enclosing walls 8a extend downwardly to a common transverse base 8b, with a rear opening and closing door 19a for access to the interior. Said walls, door, and base are of wood or other suitable material, conforming to good construction for strength, and enclosing action.

40 A vertical battery of longitudinal refrigerating pipes 33a is also located within chamber B, preferably along the front wall 8a as shown. Such pipes are conveniently in circulating connection with the pipes 33 for economical and effective operation, as will be readily understood.

The construction, operation, and advantages of the invention will be readily understood and appreciated from the foregoing description. It comprises in its entirety, 50 with either form an extremely practical, efficient, and continuously serviceable apparatus of the kind involved, composed of comparatively few parts, easily accessible, and is readily maintained in a clean, sanitary and attractive condition. By reason of the relative arrangement and location of the insulating walls the refrigerating capacity is maintained at its maximum, while the construction in other respects provides for ample and easy accessibility to the interior.

60 What I claim is:

1. In a refrigerating cabinet, the combination of a main base having a front upwardly extending sill, a rear upwardly extending wall, an intermediate upwardly extending

fixedly incorporated dividing projection providing a major containing chamber and a minor refrigerating chamber, a series of spaced apart individual supporting strips extending from the dividing projection to 70 the front sill, a shelf covering the minor refrigerating chamber and resting on the rear wall, a forwardly and upwardly sloping rear wall extending from said shelf over the major chamber to its top, a rearwardly and upwardly sloping front wall of glass extending from the front sill over the major chamber to its top, a covering shelf for the major chamber on the tops of said rear and front walls, and a continuous sheet metal lining 80 covering the inner rear wall surface and bottom of the refrigerating chamber, rounded upwardly over the dividing projection, and then continued over the bottom surface of the major chamber and the front sill and 85 terminating upwardly against the inner bottom portion of the front wall.

2. A refrigerating cabinet as described in claim 1 characterized by the location in the upper front portion of the major containing 90 chamber of supplemental refrigerating coils.

3. A refrigerating cabinet as described in claim 1 characterized by the location in the upper front portion of the major containing chamber of upper supporting shelves and 95 supplemental refrigerating coils underneath the shelves.

4. A refrigerating cabinet as described in claim 1 characterized by the presence between the major and minor chambers of a 100 longitudinal mirrored surface partition above the dividing projection with a lower intervening air circulation opening between the partition and said projection and an upper air circulation opening between the partition and the cover of the minor chamber.

5. In a refrigerating cabinet, the combination of a main base having a front upwardly extending sill, a rear upwardly extending wall, an intermediate upwardly extending fixedly incorporated dividing projection providing a major containing chamber and a minor refrigerating chamber, a series of spaced apart individual tapered supporting strips extending from the dividing partition to the front sill, a shelf covering the minor refrigerating chamber and resting on the rear wall, a forwardly and upwardly sloping rear wall extending from said shelf over the major chamber to its top, a rearwardly and upwardly sloping front wall of glass extending from the front sill over the major chamber to its top, a covering shelf for the major chamber on the tops of said rear and front walls, a continuous sheet metal lining covering the inner rear wall surface and bottom of the refrigerating chamber, rounded upwardly over the dividing projection, and then continued over the bottom surface of the major 115

120 chamber. 125

- chamber and the front sill and terminating upwardly against the inner bottom portion of the front wall, a supporting plate between the sheet metal lining and the supporting strips, and downwardly extending walls below the main base of the major and minor chambers connecting with a common supporting and enclosing bottom and enclosing a lower storage cavity, one of said walls having an opening and closing door.
6. A refrigerating cabinet as described in claim 5 characterized by the inclusion within the lower cavity of a battery of refrigerating pipes arranged adjacent one of said walls.
7. A refrigerating cabinet as described in claim 5 characterized by the incorporation therewith of skeleton supporting frame members extending upwardly at each end of the cabinet within its end walls from immediately behind the dividing projection, then forwardly inclined underneath the rear upper wall, and then forwardly beneath the covering shelf.
- In testimony whereof I hereunto affix my signature.
- JOHN EDWARD GLOEKLER.
